(57) **CLAIM**

The ornamental design for a hydraulic disc brake lever as shown and described.

DESCRIPTION

FIG. 1 is a front perspective view of a hydraulic disc brake lever showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a bottom perspective view thereof;

FIG. 9 is an enlarged detail view, showing area **9** in FIG. 1;

FIG. 10 is an enlarged detail view, showing area **10** in FIG. 2;

FIG. 11 is an enlarged detail view, showing area **11** in FIG. 3;

FIG. 12 is an enlarged detail view, showing area **12** in FIG. 4;

FIG. 13 is an enlarged detail view, showing area **13** in FIG. 7; and,

FIG. 14 is an enlarged detail view, showing area **14** in FIG. 8.

The broken lines depict portions of the hydraulic disc brake lever that form no part of the claimed design. The broken lines showing the boundaries and lead lines of the enlarged detail views form no part of the claimed design.
